Primary Examiner — Patricia A Palasik(74) *Attorney, Agent, or Firm* — McAndrews Held & Malloy, Ltd.(57) **CLAIM**

The ornamental design for a tool bit, as shown and described.

DESCRIPTION

FIG. 1 is a front perspective view of a tool bit showing my new design;

FIG. 2 is a bottom plan view thereof;

FIG. 3 is a top plan view thereof;

FIG. 4 is a right side elevation view thereof;

FIG. 5 is a left side elevation thereof;

FIG. 6 is a front elevation view thereof;

FIG. 7 is a rear elevation view thereof; and,

FIG. 8 is an enlarged view of portion 8 encircled in FIG. 1. The dashed broken lines in the drawings encircle portions of the claimed design that are illustrated in enlargements and form no part of the claimed design.

1 Claim, 4 Drawing Sheets(56)
